(57) **CLAIM**

The ornamental design for a adapter for variable air volume
damper shaft, as shown and described.

DESCRIPTION

FIG. 1 is a front perspective view of a adapter for variable air
volume damper shaft;

FIG. 2 is a rear perspective view thereof;

FIG. 3 is a top view thereof;

FIG. 4 is a bottom view thereof;

FIG. 5 is a left side view thereof;

FIG. 6 is a front view thereof; and,

FIG. 7 is a rear view thereof.

FIGS. 1-7 illustrate a adapter for variable air volume damper
shaft for use in variable air volume systems; the adapter is
used to secure a damper shaft to an actuator within the system.
The right side is unornamented.
